CLAIM

We claim the ornamental design for a closure for a container, as shown and described.

DESCRIPTION

FIG. 1 is a perspective view of a closure for a container.

FIG. 2 is a top view of the closure shown in FIG. 1.

FIG. 3 is a perspective view of a second embodiment of a closure for a container.

FIG. 4 is a top view of the closure shown in FIG. 3.

FIG. 5 is a perspective view of a third embodiment of a closure for a container; and,

FIG. 6 is a top view of the insert shown in FIG. 5.

The present application is directed to the shape and contour of a lock-out type closure for a container.

1 Claim, 6 Drawing Sheets
